UNITED STATES PATENT OFFICE.

MICHAEL O'FLANAGAN, OF ROSCOMMON, IRELAND.

SUSPENSION SUPPORT FOR BEDS AND THE LIKE.

Application filed June 12, 1922. Serial No. 567,750.

To all whom it may concern:

Be it known that I, MICHAEL O'FLANAGAN, a citizen of Ireland, residing in Roscommon, in the county of Roscommon, Ireland, have 5 invented certain new and useful Improvements in Suspension Supports for Beds and the like, for which the following is a full and complete specification, reference being had to the accompanying drawings.

10 This invention relates to a mode of suspending a bed, couch, chair or the like in such manner that the bed or other device will tend to remain in a predetermined and preferably horizontal plane irrespective of outside forces.

Specifically, my invention is addressed to remedying the rigidity of the support for a bed, chair or the like upon shipboard. The 15 rolling and pitching of a vessel causes seasickness or other discomforts resulting from the inability of the human system to adapt itself to the rapid changes in inclination of the deck of the vessel. Where the support, such as a bed or chair, rests or is connected 20 directly to the deck or walls of the vessel, the changes in inclination of the vessel are transmitted to the passenger directly and without diminution of force. Consequently, the passenger is called upon to make the 25 entire adjustment in position or to balance or brace himself to overcome the influence of the movements of the ship.

I have discovered that the movements of the ship may be substantially neutralized by 30 supporting the chair or bed through means which permit the article of furniture to remain in a substantially horizontal plane or predetermined inclination regardless of the ship's movements. This is accomplished by 35 so proportioning the suspending structure as to take advantage of the most desirable swinging movements. For example, in the case of a swinging berth on shipboard where the longitudinal axis of the berth is parallel 40 to the direction of ship's travel the radius of relative movement in this plane between berth and the ship is the full vertical distance from the berth to the ceiling or beam from which it is suspended. The arc of 45 oscillation is slight and does not ordinarily exceed approximately ten degrees. This movement may be likened to the motion of a pendulum having the indicated length and oscillation. When the occupant of the 50 berth moves upon it, the center of gravity of the berth and its load is necessarily 55

shifted but due to the length of the pendulum the amount of angular adjustment is slight while the berth may be displaced longitudinally for a material distance. 60

In the same example the lateral rolling of the ship is compensated for by the suspension of the berth from a relatively short pendulum having, in comparison with the above mentioned movement, a relatively 65 larger arc of oscillation and shorter lateral displacement. It will be noted that the shortness of the pendulum for lateral adjustment, reducing the lateral displacement, reduces the space or clearance necessary 70 between adjacent berths. Throughout the following description it will be obvious that the purpose of the device is to stabilize the article of furniture or to minimize its adjusting movements and that the operation 75 differs from the analogy of a pendulum because the article and its suspending means tend to remain in a vertical plane with respect to the horizon while the ship varies its inclination thereto. The analogy applies 80 however in all respects so far as the angles of adjustment are concerned.

Another object of my invention is to so proportion the various elements of the suspension or support that a minimum amplitude or arc of movement is required to retain the supported structure in the desired 85 position.

A device constructed according to my invention has marked advantages in economy, 90 ease of manufacture and readiness of manipulation. Its portability adapts it as well for transport and use by the individual passenger, as for installation by the ship-owner. 95

Other advantages of my invention will be evident from the following description and drawings in which I have illustrated one preferred form which my invention may take. 100

In the drawings,

Fig. 1 is a side elevation of one form of my suspension means as applied to a swinging bed or berth.

Fig. 2 is an end elevation of the same; 105

Fig. 3 is a detailed view of one form of fastening;

Fig. 4 is an end view of the same; and

Fig. 5 is a perspective view showing this invention as applied to a swinging chair or 110 seat.

As illustrated in the drawings, the sup-

port consists of a bar 7 connected intermediate the berth, chair or other article to be suspended and the part of the vessel or other structure from which the article is suspended. 5 As above outlined, the direction which the bar takes with respect to the axis of the berth is dependent upon the direction in which the maximum oscillations occur and upon the clearance allowed the berth. For 10 example, as shown in Fig. 1, where the article takes the form of a rigid bed or berth, which it is desired to support in relatively stationary position with respect to the horizontal plane regardless of the vibration and 15 oscillation of the vessel, the bar is placed along the longitudinal axis of the bed or berth. This brings the bar normally parallel with the longitudinal axis of the vessel, the advantage of which will be brought 20 out hereinafter. The bar 7 may be of tubular metal, wood or other analogous material. Each end of the bar has a cap in the form of a hollow casting one end of which may be closed to form a cavity receiving the 25 end of the bar 7. This casting 8 has two eyelets 9 and 10 on opposite sides.

Eyebolts 11, each having an eye 12, are fastened in the ceiling 13 of the vessel. These eyebolts are spaced substantially the 30 width of the berth which is to be supported and laterally of the vessel as shown in Fig. 1.

A cable, rope, chain, rod or analogous member 14 is fastened in the eye 12 of one 35 eyebolt and extends to the eyelet 9 of the casting 8. The member 14 when made of flexible material then forms a bight around the free end of the casting 8 passing through the eyelet 9 in the opposite direction and thence by means of end 15 of the member is 40 connected to the eyelet 12 of the opposite bolt 11. Two members 14, 15 pass from each eyelet 12, one member 14 going to each casting 8 at opposite ends of the bar 7 and returning with its free end 15 to the opposite eyelet 12. The lengths of the cables are such as to produce a tetrahedron having as 45 its apices the castings 8 and the eyebolts 11. The manner in which the members 14 are 50 wrapped around the free ends of the castings 8 permit of ready adjustment to allow for any inequality or irregularity in the plane of the eyebolts 11 or the upper deck 55 13. The bight of the member 14 establishes frictional engagement with the casting 8 in such manner as to retain any adjustment made. A cable 16 depends from each casting 8 and has free ends 17 and 18. The end 60 17 passes through eyelet 10 of casting 8 around the casting and through eyelet 10 in the opposite direction from free end 18. The ends 17 and 18 are fastened to stands 65 19 on the berth, hammock or other article 20. The bight of member 16 is readily adjusted around casting 8 and maintains

frictional engagement therewith. A member 16 depends from each casting 8 and thus supports both ends of the structure 20.

The form of casting 8 is shown in Fig. 4 to be constructed with eyelets 9 and 10 on 70 opposite sides of the casting and in the same plane at right angles to the cooperating bar 7. The member 14 is brought through the upper eyelet 9 around the casting and back through eyelet 9, as shown, to form the free end 15. The member 16 has its free ends passing through the lower eyelet 12 as indicated to form the free ends 17 and 18. The free ends of the flexible members 14-18 are 75 connected as indicated in Fig. 2.

Where it is desired to use this form of suspension for a chair 21 as shown in Fig. 5, it is preferable to place the bar 7 parallel to the chair back with the corresponding change in position of the flexible members 80 14-18 inclusive. This provides ample space to avoid interference with the occupant and maintains the desirable relation between the long and short radii of adjustment as above 85 described.

When installed in the manner described, the support of the bed or other article of furniture is maintained through a tetrahedron the opposite edges of which form pivotal lines of adjustment at right angles 90 each to the other. The oscillation of the vessel is therefore resolved into motion in two perpendicular planes. The edge of the tetrahedron represented by a line drawn between the eyes 12, 12, forms a pivot around 95 which the vessel is adjusted angularly with respect to the supported device, which tends to remain in a vertical plane by its own gravity. This is illustrated most simply 100 where the center of oscillation of the vessel coincides with the line between the eyes 12, 12 as in Fig. 1, although the same adjustment will occur if the center of oscillation 105 be any line in the plane of the deck 13. In the case that this center is inclined to the 110 said line then the oscillation is compensated for partly by the pivot 12, 12 and partly by the lower pivot 8, 8, some slight vertical and lateral displacement also occurring.

The bar 7 is therefore stabilized in one 115 direction and subject only to oscillation in a direction at right angles thereto. As this bar forms one edge of the tetrahedron it permits pivotal movement of the line 12, 12 120 without material disturbance to the device suspended from the bar. This compensating action is shown in Fig. 2 in which the roll of deck 13 is transmitted through bar 7 to cause only a slight lateral and vertical 125 displacement of the berth 20. This is true where the center of rolling oscillation is other than on the longitudinal vertical plane of 20 and any obliquity of the center to this pivot will be resolved into movement 130 along the pivots 12, 12 and 8, 8.

It will be seen that in this arrangement of elements, the bed, chair or the like is rendered substantially free from pivotal movement transmitted from the swinging or swaying action of the vessel. The influence of the vessel's movement is fully neutralized by the action of the two pivotal edges of the tetrahedron of support while only a slight lateral and vertical displacement results. The occupant is unaffected by the movement of the vessel.

By lengthening element 14 and shortening element 15 by a corresponding degree the normal inclination of the berth to the horizontal plane may be varied as desired. The weight of the berth will retain these in adjusted position by the frictional engagement between the elements and the castings 8.

While I have illustrated one form in which my invention may be embodied, yet it will be evident that many changes in minor details may be made without departing from the scope of the invention as defined in the appended claims. For example the conventional hammock may be adapted to be suspended in this manner by attaching the elements 17 and 18 to the ends of the hammock stretchers. Again the elements 14, 15, 16, 17 and 18 may be rigid with suitable pivotal attachments at the bar 7 and eyes 12, 12.

What I claim is:

1. In combination with a freely swinging bed supporting means therefor arranged tetrahedrally, said means being pivotally connected at opposite edges to the supporting structure and the bed respectively.
2. In combination with a freely swinging bed supporting means therefor arranged tetrahedrally, said means being pivotally connected at one edge to a supporting structure and being pivotally connected to the bed at another edge at right angles to and in a plane parallel to said first named edge.

3. In combination with a freely swinging bed suspending elements therefor, a bar to which the elements are attached and about which they are adapted to swing in a vertical plane, connecting elements between said bar and a supporting structure, said connecting elements being attached to said supporting structure on a single axis inclined with respect to the vertical plane of said bar.

4. In combination with a freely swinging bed, flexible suspending elements therefor, a bar to which the elements are attached and about which they are adapted to swing in a vertical plane, connecting elements between said bar and a supporting structure, said connecting elements being attached to said supporting structure on a single axis inclined with respect to the vertical plane of said bar.

5. In combination with a freely swinging bed, two flexible members attached at their ends to the respective ends of the bed, a bar lying in the vertical plane through one axis of the bed and having means for adjustable frictional engagement with the flexible members and suspending means for said bar on a single axis inclined to said plane.

6. In combination with a freely swinging bed, two flexible members each attached at their ends to two adjacent corners of the bed, a bar, means on each end of the bar to receive the mid-portions of the flexible members, and suspending elements for attaching said means to a supporting structure pivotal at an angle to the bar.

7. In combination with a freely swinging bed, a bar, castings on the ends of the bar, each casting having diametrically opposed eyelets, and connecting means passing through the eyelets for attachment to the bed and to the supporting structure.

In testimony whereof I have hereunto affixed my signature.

MICHAEL O'FLANAGAN.
